W. O. BANDLOW,
FURNACE ATTACHMENT,
APPLICATION FILED FEB. 1, 1919.

1,318,639.

Patented Oct. 14, 1919.

INVENTOR:
Walter O. Bandlow
By his attorney:
Charles S. Gooding.

UNITED STATES PATENT OFFICE

WALTER O. BANDLOW, OF HYDE PARK, MASSACHUSETTS.

FURNACE ATTACHMENT.

1,318,639.

Specification of Letters Patent.

Patented Oct. 14, 1919.

Application filed February 1, 1919. Serial No. 274,503.

To all whom it may concern:

Be it known that I, WALTER O. BANDLOW, a citizen of the United States, residing at Hyde Park, in the county of Suffolk and 5 State of Massachusetts, have invented new and useful Improvements in Furnace Attachments, of which the following is a specification.

This device relates to attachments for 10 furnaces, heaters and the like and is adapted to be attached to the smoke pipe or flue between the usual damper and the combustion chamber.

The object of the invention is to provide a 15 simple and inexpensive device for introducing air into the flue in such a manner that there will be a more complete and perfect combustion of the gases which are generated within the furnace and which generally pass 20 unconsumed from said furnace through said flue.

Another object of this invention is to provide means whereby the amount of air admitted to the flue may be regulated. Still 25 another object of this invention is to so construct the device that it will require a minimum amount of machine work and labor in finishing and assembling the various parts and will not require the services of a skilled 30 mechanic in attaching it to the flue.

The invention consists in the combination and arrangement of parts set forth in the following specification and particularly pointed out in the claims thereof.

Referring to the drawings:

Figure 1 represents the side elevation of a 40 furnace with a smoke flue leading therefrom upon which is mounted my improved furnace attachment.

Fig. 2 is a front elevation of said furnace attachment.

Fig. 3 is a central vertical section taken on the line 3—3 of Fig. 2.

Fig. 4 is a transverse section taken on the 45 line 4—4 of Fig. 2.

Fig. 5 is a view similar to Fig. 4 illustrating an alternative method of applying my improved attachment to a smoke flue.

Like numerals refer to like parts throughout the several views of the drawings.

In the drawings, 10 represents a furnace, of any desired type or construction, the same being provided with the usual combustion chamber 11 from which extends a smoke 55 flue 12. A damper 13 of any desired construction is located in the smoke flue 12.

Upon the exterior of the flue 12 between the damper 13 and the combustion chamber 11 is detachably mounted a yoke 14 by means of a rod 15 and nuts 16, the rod being bent 60 to extend around the flue 12 and pass through ears 17 upon opposite extremities of the yoke 14. The yoke 14 preferably conforms at 18 with the curvature of the flue 12. Integral with the yoke 14 is a cylindrical 65 flange 19 having oppositely disposed openings 20 formed therein.

A cup-shaped member 21 is rotatably mounted upon the yoke 14, said cup-shaped member 21 having a cylindrical flange 22 70 which is adapted to fit and turn upon the flange 19. The flange 22 is provided with oppositely disposed openings 23. The cup-shaped member 21 mounted upon the yoke 14 co-operates with said yoke to form a 75 chamber 24 and said member 21 being rotatably mounted upon the flange 19 will co-operate with said yoke to regulate the amount of air which will enter the chamber 24 through the openings 20 and 23. An elbow 80 25 which constitutes an air delivery pipe is arranged to deliver air from the interior of the chamber 20 to the interior of the flue 12. The elbow 25 is constructed with an arm 26 and an arm 27 at right angles thereto. 85 The arm 26 passes through an opening 28 in the flue 12 and an opening 29 in the center of the yoke 14, the center line of said arm 26 being co-incident with the center line of the cylindrical flange 19 and the cylindrical flange 22.

Openings 30 are provided adjacent to the end of the arm 26 said openings 30 being arranged at an angle of 90 degrees to the openings 20 which are provided in the yoke 95 14. The elbow 25 together with the cup-shaped member 21 is secured to the yoke 14 by means of a bolt or rivet 31. The arm 27 of the elbow 25 is arranged in the smoke flue 12 with its open end 33 directed toward 100 the combustion chamber 11 of the furnace 10.

The operation of my improved furnace attachment is as follows: An opening 28 is made in the smoke flue 12 between the damper 13 and the furnace and through this 105 opening is inserted the elbow 25 with its arm 27 directed toward the combustion chamber 11. The yoke 14 is then clamped to the smoke flue by means of the rod 15 and nuts 16, the entire operation being so 110 simple as not to require the services of a skilled mechanic.

Air entering the chamber 24 through the openings 20 and 23 will pass from the chamber 24 through the openings 30 in the elbow 25 and thence will be directed through 5 said elbow to the interior of the flue 12. When it is intended to check the fire within the furnace as for instance when leaving it for the night, the damper 13 is closed and the air entering the flue 12 through the air 10 delivery pipe 25 will act to form a cushion between the end of the arm 27 and the damper 13 which will act to retard the gases which generally pass unconsumed through said flue and thereby cause a more 15 perfect combustion of said gases in the combustion chamber of the furnace. The ordinary suction upon the fuel in the furnace which is caused by the draft up the flue is also lessened because of the fact that said 20 draft will not act in as direct a manner upon the furnace but will tend to draw upon the air which is entering the flue through this device.

In Fig. 5 I have illustrated a somewhat 25 modified method of attaching my device to the smoke flue. In this figure a member 35 is provided with a flange 36 and said flange is riveted to the smoke flue 12 by means of rivets 37. The member 35 in other respects 30 is similar to the yoke 14 previously described. All the other parts of the device illustrated in Fig. 5 are exactly the same as has been previously described in connection with Figs. 1 to 4 inclusive, and the 35 operation of the device is the same in every respect.

Having thus specifically described my invention, what I claim and desire by Letters Patent to secure is:

- 40 1. An attachment for a heating device having, in combination, a smoke flue, a yoke attached to said smoke flue having integral therewith, a cylindrical flange, a cup-shaped member superimposed upon said yoke and coöperating therewith to form a chamber, and an air delivery pipe adapted to deliver air from said chamber to the interior of said smoke flue in the direction of said heating device.
- 45 2. An attachment for a furnace having, in combination, a flue, a yoke detachably mounted upon said flue having integral therewith a cylindrical flange, an air delivery pipe entering said flue through said yoke, and a cup-shaped member rotatably mounted upon said yoke and adapted to regulate the amount of air entering said air delivery pipe.

55 said cylindrical flange the inner end of said air delivery pipe being open toward said furnace, and a cup-shaped member rotatably mounted upon said cylindrical flange and adapted to coöperate with said flange to regulate the amount of air entering said air delivery pipe.

5. An attachment for a furnace having, in combination, a flue, a yoke detachably mounted upon said flue, said yoke having integral therewith a cylindrical flange, a 60 cup-shaped member rotatably mounted upon said yoke and coöperating therewith to form a chamber, and an air delivery pipe entering said flue through said yoke, said air delivery pipe being constructed in the form of an 65 elbow, one arm of said elbow being adapted to receive air from the exterior of said flue through said chamber and the other arm of said elbow being adapted to deliver said air to the interior of said flue in the direction 70 of said furnace.

4. An attachment for a furnace having, in combination, a flue, a yoke detachably mounted upon said flue, said yoke having integral therewith a cylindrical flange, 80 openings in said flange, a cup-shaped member rotatably mounted upon said yoke and coöperating therewith to form a chamber, openings in said cup-shaped member adapted to coöperate with the openings in 85 said flange and thereby regulate the amount of air entering said chamber, and an air delivery pipe adapted to deliver air from the interior of said chamber to the interior of said flue in the direction of said furnace. 90

5. A heating device having, in combination, a combustion chamber, a flue leading therefrom, a damper located in said flue, a yoke attached to said flue having integral therewith a cylindrical flange, an air delivery pipe entering said flue through said yoke, and a cup-shaped member rotatably mounted upon said yoke and adapted to regulate the amount of air entering said air delivery pipe. 95

100 In testimony whereof I have hereunto set my hand in presence of two subscribing witnesses.

WALTER O. BANDLOW.
